UNITED STATES PATENT OFFICE.

GEORGE W. LEWIS, OF FRANKFORD, PENNSYLVANIA.

TOY FURNITURE.

SPECIFICATION forming part of Letters Patent No. 251,903, dated January 3, 1882.

Application filed April 22, 1881. (No model.)

To all whom it may concern:

Be it known that I, GEO. W. LEWIS, a citizen of the United States, residing at Frankford, in the county of Philadelphia and State of Pennsylvania, have invented certain new and useful Improvements in Toy Furniture; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

Figures 1 and 3 are views of the chair and its blank, and Figs. 2 and 4 are views of the sofa and its blank.

This invention has reference to the manufacture of toy articles of furniture; and it consists in the construction and adaptation of the blank for the intended purpose, substantially as hereinafter more fully set forth.

Referring to the accompanying drawings by the way of illustrating my invention, I will describe its application to the following among other toy articles of furniture.

A is the chair, which is made from the blank A' as follows: fold at F, bringing E and G together, then bend at C, downward again at B and K, bringing K over A and the two ends together, and again at E and G, forming the front legs; next bend at H and B upwardly, forming the back of the chair and finishing the operation of making the chair.

B is a sofa, which is made from the blank B' in the following manner: commencing at A 35 bend downward, and again downward at C, then upward at D and downward at F, again bending at G, which brings H and B together, forming one arm of the sofa; then bend at I 40 downward, again at K downward, and at L, when the other arm of the sofa will be formed; finally bend at O upward, folding it over A, which will bring the two ends A O together, thus completing the operation of making the 45 sofa.

It will be noticed that the configurated apertures indicated by letters in the blanks add an ornamental appearance to the several articles of furniture, in addition to facilitating 50 and preventing the least possible distorting of the tin while bending the same.

Having thus fully described my invention, I claim and desire to secure by Letters Patent—

As a new toy article of manufacture, the blank 55 having a series of continuous apertures which indicate the points at which it is to be bent into the intended shape, and bent and folded upon itself continuously in the formation of the seat, legs, and back of the article, as shown and described.

In testimony whereof I affix my signature in presence of two witnesses.

GEORGE WASHINGTON LEWIS.
